(57) **CLAIM**

We claim, the ornamental design for a display screen or portion thereof with animated graphical user interface, as shown and described.

DESCRIPTION

FIG. 1 is a first image in a sequence for a display screen or portion thereof with animated graphical user interface showing our new design;

FIG. 2 is a second image in a sequence thereof;

FIG. 3 is a third image in a sequence thereof;

FIG. 4 is a fourth image in a sequence thereof;

FIG. 5 is a fifth image in a sequence thereof;

FIG. 6 is a sixth image in a sequence thereof;

FIG. 7 is a seventh image in a sequence thereof;

FIG. 8 is an enlarged view of a first image in a sequence of the claimed portion thereof in FIG. 1;

FIG. 9 is an enlarged view of the claimed portion thereof in FIG. 2, which is the second image in a sequence thereof;

FIG. 10 is an enlarged view of the claimed portion thereof in FIG. 3 which is the third image in a sequence thereof;

FIG. 11 is an enlarged view of the claimed portion thereof in FIG. 4 which is the fourth image in a sequence thereof;

FIG. 12 is an enlarged view of the claimed portion thereof in FIG. 5 which is the fifth image in a sequence thereof;

FIG. 13 is an enlarged view of the claimed portion thereof in FIG. 6 which is the sixth image in a sequence thereof; and,

FIG. 14 is an enlarged view of the claimed portion thereof in FIG. 7 which is the seventh image in a sequence thereof.

The broken line showing of the display screen or portion thereof is for the purpose of illustrating environment and forms no part of the claimed design. The broken line showing of elements on the display screen illustrate portions of the article and form no part of the claimed design. The dot dash lines in the figures represent an unclaimed boundary line and form no part of the claimed design.

The appearance of the transitional image sequentially transitions between the images shown in FIGS. 1-7. The process or period in which one image transitions to another image forms no part of the claimed design.
